DESIGN FOR A DRESS

Henry J. Pearl, Los Angeles, Calif., assignor of one-half to Harvey L. Barker, Los Angeles, Calif.

Application March 3, 1942, Serial No. 106,070

Term of patent 14 years

To all whom it may concern:

Be it known that I, Henry J. Pearl, a citizen of the United States, residing at Los Angeles, in the county of Los Angeles and State of California, have invented a new, original, and ornamental Design for a Dress, of which the following is a specification, reference being had to the accompanying drawing, forming part thereof.

Fig. 1 is a front view in elevation of a dress showing my new design.

Fig. 2 is a view in elevation showing the back of the dress of Fig. 1.

I claim:

The ornamental design for a dress, substantially as shown.

HENRY J. PEARL.
